Primary Examiner — Holly Baynam(74) *Attorney, Agent, or Firm* — Harness, Dickey & Pierce, P.L.C.(57) **CLAIM**

The ornamental design for a track for a shelving system, as shown and described.

DESCRIPTION

FIG. 1 is an upper perspective view of a track for a shelving system, showing my new design;

FIG. 2 is a lower perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines showing openings are for the purpose of illustrating environment and form no part of the claimed design. The broken lines immediately adjacent the shading represent the bounds of the claim and form no part of the claimed design.
